COLLAPSIBLE ROLLER

Cy Martin, Douglaston, N.Y.

Application June 4, 1956, Serial No. 589,047

11 Claims. (Cl. 242—55.2)

This invention relates to small, collapsible rollers or rotatable supports, and more particularly to rollers or rotary supports of the type adapted to carry rolls of paper such as toilet tissue and the like.

An object of the invention is to provide an improved and simplified collapsible roller for use with existing paper holders, which roller greatly facilitates and simplifies the operation of removing the empty paper core and replacing the same with a full roll of paper.

Another object of the invention is to provide an improved collapsible roller as above set forth, wherein the operation of removal and replacement is extremely simple and easy to understand.

A further object of the invention is to provide a novel and improved collapsible roller in accordance with the above, which is characterized by relatively few, easily fabricated components.

Yet another object of the invention is to provide an improved collapsible roller of the above type, which is reliable in use and not likely to get out of order easily.

Still another object of the invention is to provide an improved collapsible roller adapted to provide various degrees of restraint or braking action on the paper roll carried thereby.

Yet another object of the invention is to provide an improved collapsible roller in accordance with the above, which has a novel hinge action to release it from the holder.

A feature of the invention resides in the provision of an improved collapsible roller which may be used with a wide variety of types and styles of holders.

Another feature of the invention resides in the provision of a novel collapsible roller having all of the above advantages and which is nevertheless simple and economical to fabricate or produce.

Other features and advantages will hereinafter appear.

In the drawings accompanying this specification, similar characters of reference indicate corresponding parts wherever possible in the several views, in which:

Figure 1 is an axial sectional view of an improved collapsible roller made in accordance with the invention, shown positioned in a holder and carrying an empty paper core.

Fig. 2 is an axial sectional view of the roller of Fig. 1, with the paper core being collapsed prior to removal of the holder.

Fig. 3 is a view similar to Figs. 1 and 2 but showing the roller further collapsed and ready to be removed from the holder.

Fig. 4 is an axial sectional view of a collapsible roller made in accordance with the invention but illustrating another embodiment thereof.

Fig. 5 is an axial sectional view of a collapsible roller illustrating still another embodiment of the invention.

Fig. 6 is a fragmentary view of a portion of a collapsible roller, showing a further modification of the invention.

2

Fig. 7 is a view like Fig. 6 but illustrating yet another modification.

Fig. 8 is a fragmentary sectional view of a portion of a collapsible roller showing yet another modification.

Fig. 9 is a fragmentary sectional view illustrating still another modification.

Figs. 10, 11 and 12 are fragmentary axial sectional views illustrating modified forms of bearing means on the end members of the rollers.

Fig. 13 is an axial sectional view of a roller illustrating yet another embodiment of the invention.

Referring to Fig. 1, the improved collapsible roller of this invention comprises a pair of axially-aligned end members 20 and 21 having bearing means in the form of projections 22 and 23 respectively, adapted to be received in, and to turn in recesses 24 of a holding device 25. The end members 20 and 21 have coupling portions 26 and 27 respectively, disposed in opposite relation to each other, said coupling portions being shown as in 20 the form of axially-aligned shanks projecting toward each other.

By the present invention I provide a novel and improved coupling means in conjunction with the coupling portions 26 and 27 of the roller, to enable the end members 20 and 21 to have relative arcuate movement whereby said members may be swung or hingedly shifted to collapse the roller and remove it from the holding device 25. This coupling means may have various forms and specific functions, in addition to the general function of providing a hinged connection. In Figs. 1-3 the coupling means comprises a helical coil spring 30, the ends of which are carried on reduced portions 31 and 32 of the shanks 26 and 27 respectively. Also, the coupling means comprises an extension 33 on the reduced shank 32, having an elongate, axially-extended slot 34 provided with a cut 35 in its wall. A second extension 36 is provided on the reduced shank 31, such extension 36 passing through the slot 34 of the extension 32 and also having a slot 37.

40 It will be noted that assembly of the parts 33 and 36 may be accomplished by passing the extremity of the part 36 through the cut 35 in the part 33. For this purpose sufficient clearance is provided between the compression spring 30 and the portions 32 and 33 of the shank 27, to permit passage of the extremity of the shank part 36 through the spring and through the cut 35, thereby to enable said extremity to be brought into the slot 34. Preferably, when the various components are 45 assembled as shown in Fig. 1, the spring 30 is under a slight amount of compression, whereby it will retain the slotted parts in the relative positions shown, and maintain separated the end members 20 and 21.

In actuating the collapsible roller shown in Figs. 1-3 to remove the same from the holder 25 upon exhaustion of the paper, it is merely necessary to squeeze together the center portions of the cardboard core 39 which formed part of the paper roll, as shown in Fig. 2, and thereafter to hingedly collapse the roller as shown in Fig. 3, whereupon it may be readily removed from the holding device 25. It will be readily understood that such operation may be simply and quickly performed, and does not require any unusual strength in the fingers, or any special skill on the part of the user.

Assembly of the roller to a new roll of paper is accomplished in the usual manner, by slipping the roller through the cardboard core of the paper roll, and then applying the assembly to the holding device 25 while depressing one or both ends of the roller by axial pressure on the end members 20 and 21. Preferably such end members are provided with radially extended flanges 40 and 41 respectively, having rims 42 and 43 by which the core 39 may be supported and properly positioned,

the flanges 40 and 41 providing finger-engageable surfaces by which axial end pressure may be readily applied during the assembling of the roller to the holding device 25.

The roller shown in Figs. 1-3 has a predetermined axial length which is slightly less than the spacing between corresponding portions of the holding device 25 whereby the roller is loosely carried in said device and is free to turn upon the application of the slightest turning moment.

Another embodiment of the invention is shown in Fig. 4, wherein end members 20a and 21a have coupling portions 26a and 27a, in which there are embedded the ends of a coupling chain 45 and also a helical compression spring 30. The spring 30 is normally under compression, as effected by the chain 45, and the latter in conjunction with the spring enables the end members 20a and 21a to have angular collapsing movement similar to that illustrated in Fig. 3, whereupon the roller and empty cardboard core carried thereby may be readily removed from the holding device 25.

Another embodiment of the invention is shown in Fig. 5, wherein end members 20b and 21b are connected to each other by a chain 45 and held in separated positions by a helical compression spring 30, the ends of which abut shank portions 26b and 27b of the members 20b and 21b.

To provide a support for the cardboard core 39, the end members 20b and 21b have radially-extended flanges 40 and 41b, and a second set of flanges 47 and 48 is provided, spaced from the flanges 40b and 41b and adapted to frictionally engage the opposite faces 49 and 50 of the holding device 25, thereby to provide a frictional restraint on the roller and prevent the latter from having perfectly free turning.

The collapsing movement of the roller shown in Fig. 5 is generally similar to that depicted in Fig. 3, wherein the end members of the roller may have relative arcuate movement.

Another embodiment of the invention is shown in Fig. 6. In this figure the reduced extensions 31 and 32 of the shanks 26 and 27 may be made respectively integral, as distinguished from the construction shown in Fig. 1, wherein the extensions 31 and 32 are formed as separate pieces and attached to the shanks in any suitable manner as by screwing, soldering, press fitting and the like.

Another embodiment of the invention is illustrated in Fig. 7, wherein the coupling means comprises in addition to the spring 30 a pair of elongate chain links 36c and 33c, said links being embedded in the shanks 26c and 27c of the end members.

Yet another embodiment of the invention is illustrated in Fig. 8, wherein an end member 21d has an integral shank 32d provided with an integral slotted extension 33d, and wherein the compression spring 30 is anchored to the shank 32d by the end 52 of the spring passing through the shank and being turned over, as at 53.

Still another embodiment of the invention is illustrated in Fig. 9, wherein an end member 21e is provided with an axial bore 54 in which a coil spring 55 is disposed, and in which a retractile bearing pin 56 is carried, said bearing pin having a slot 57 and being held captive by a cross pin 58 passing through the slot 57 and anchored in the member 21e. With this construction the bearing pin 56 may be depressed during the operation of reinserting the roller in the holding device.

Another embodiment of the invention is illustrated in Fig. 10, wherein end members 20f and 21f have shank or coupling portions 26f and 27f respectively, in which there are embedded the ends of the spring 30, such spring constituting the sole coupling means between the end members. The members 20f and 21f have end flanges 40f and 41f, together with bearing projections 22f and 23f. The flanges 40f and 41f do not have rims such as are shown in Figs. 1-3, but instead are spaced apart a distance slightly greater than the length of the cardboard

core 39. Thus the core 39 will ride on the shank portions 26f and 27f of the roller and engage a much smaller diameter than that of the rims 42 and 43. A retarding or braking effect is thus provided, whereby the roll of paper may not turn as freely as with the embodiment of Figs. 1-3 since the roller movement is speeded up due to its being driven on a smaller diameter by the paper roll.

Another embodiment of the invention similar to that shown in Fig. 10 is depicted in Fig. 11. The difference between these two embodiments resides in the elimination in Fig. 11 of the bearing projections 22f and 23f of Fig. 10. Instead, the flange 41g in Fig. 11 of the end member 21g constitutes the bearing surface which engages the holding device 25. Thus a large-diameter bearing is provided between the roller and the holder 25, whereas a small diameter bearing is provided by the shank 27g, between the roller and the cardboard core 39. In consequence, the opposing frictional force or moment provided by the flange 41g is greatly increased over the opposing moment provided by the pin 23f in Fig. 10, and as a result a much greater braking or retarding action is provided.

Fig. 12 illustrates another embodiment of the invention wherein a simplification is effected of the structure shown in Fig. 10, by the elimination of the flange 41f thereof. In Fig. 12 each end member 21h constitutes a shank of substantially uniform diameter acting as a bearing engaging both the cardboard core 39 and also the holding device 25. A desirable economy of manufacture is thus effected, while at the same time a predetermined amount of retarding or braking action is had.

Yet another embodiment of the invention is shown in Fig. 13, wherein end members 20j and 21j are connected to each other for relative arcuate movement by a coupling means comprising a length of flexible rubber hose or tube 60, the ends of which are press-fitted over shank portions 26j and 27j of the members, as shown. It will be understood that, instead of the rubber tubing 60 a solid bar of flexible rubber may be provided, press-fitted into axial bores in the shanks 26j and 27j, such shanks being for this purpose of larger diameter. Also, the entire collapsible roller shown in Fig. 13 may be constructed of flexible rubber, instead of being fabricated of separate components with the coupling means thereof only constituting flexible rubber.

It will be readily understood from a consideration of the above structures that I have provided a novel and improved, simple, reliable and easy-to-operate collapsible roller adapted to function in conjunction with relatively small rolls of paper or other like articles. The components illustrated in the various embodiments of the invention are simple and easy to fabricate and assemble, and the various rollers may be manufactured at low cost. They are characterized essentially by the provision of two end members and a coupling means connecting said members, which permits relative arcuate movement between the members for the purpose of facilitating removal of the roller from a holding device without requiring movable parts on the latter, or requiring abnormal strength in the fingers or skill on the part of the user.

Variations and modifications may be made within the scope of the claims and portions of the improvements may be used without others.

I claim:

1. A collapsible roller comprising a pair of axially-aligned end members having bearing means for engagement with bearings of a holding device, said members having coupling portions disposed opposite each other; and pivot-action coupling means comprising a plurality of rigid and inflexible, non-extensible linked members at least two of which are respectively connected to said coupling portions, movably joining the said end members to each other and providing for relative arcuate movements thereof, thereby to enable the members to be ap-

plied to and removed from the holding device by relative arcuate movement of the members.

2. The invention as defined in claim 1 in which there is a helical coil spring having its ends rigidly secured to the coupling portions of the end members surrounding said coupling means. 5

3. The invention as defined in claim 1 in which the end members have radially extending flanges adapted to engage an article carried by the roller.

4. The invention as defined in claim 1 in which the end members comprise short rods of substantially uniform diameter. 10

5. A collapsible roller comprising a pair of axially-aligned end members having bearing means for engagement with bearings of a holding device, said members having coupling portions disposed opposite each other; and pivot-action coupling means connected to said coupling portions, movably joining the said end members to each other and providing for relative arcuate movements thereof, thereby to enable the members to be applied to and removed from the holding device by relative arcuate movement of the members, said coupling means comprising a helical coil spring having its ends rigidly secured to the coupling portions of the end members, and further comprising an articulated link having a pair of rigid parts connected to said coupling portions. 15 20 25

6. A collapsible roller comprising a pair of axially-aligned end members having bearing means for engagement with bearings of a holding device, said members having coupling portions disposed opposite each other; and pivot-action coupling means connected to said coupling portions, movably joining the said end members to each other and providing for relative arcuate movements thereof, thereby to enable the members to be applied to and removed from the holding device by relative arcuate movement of the members, said coupling means comprising an articulated link having rigid parts connected to said coupling portions, and further comprising a helical compression spring, the ends of which engage the said coupling portions. 30 35 40

7. The invention as defined in claim 6 in which one of the rigid parts of the articulated link has a slot through which the other part extends.

8. A collapsible roller comprising a pair of axially-aligned end members having bearing means for engagement with bearings of a holding device, said members having coupling portions disposed opposite each other; and pivot-action coupling means connected to said cou- 45

pling portions, movably joining the said end members to each other and providing for relative arcuate movements thereof, whereby to enable the members to be applied to and removed from the holding device by relative arcuate movement of the members, said end members having radially extending flanges adapted to engage an article carried by the roller, and said coupling portions of the members comprising shanks extending from the flanges in directions toward each other.

9. The invention as defined in claim 8 in which the bearing means of the end members comprise projections extending axially from the said flanges thereof.

10. A collapsible roller comprising a pair of axially-aligned end members having bearing means for engagement with bearings of a holding device, said members having coupling portions disposed opposite each other; and pivot-action coupling means connected to said coupling portions, movably joining the said end members to each other and providing for relative arcuate movements thereof, thereby to enable the members to be applied to and removed from the holding device by relative arcuate movement of the members, said coupling means comprising a link joining the end members to each other and a helical compression spring surrounding the link and engaging the coupling portions of the end members, said spring being continually held in compression by said link.

11. A collapsible roller comprising a pair of axially-aligned end members having bearing means for engagement with bearings of a holding device, said members having coupling portions disposed opposite each other; and pivot-action coupling means connected to said coupling portions, movably joining the said end members to each other and providing for relative arcuate movements thereof, thereby to enable the members to be applied to and removed from the holding device by relative arcuate movement of the members, said bearing means of the members comprising axial projections, and said coupling portions comprising shanks aligned with said projections, said shanks and projections being of commensurate diameters.
